UNITED STATES PATENT OFFICE.

CHARLES T. WAGNER, OF BROOKLYN, NEW YORK.

MANUFACTURE OF QUILTED LINING.

SPECIFICATION forming part of Letters Patent No. 425,717, dated April 15, 1890.

Application filed February 16, 1888. Renewed March 5, 1890. Serial No. 342,805. (No model.)

To all whom it may concern:

Be it known that I, CHARLES T. WAGNER, of Brooklyn, county of Kings, State of New York, have invented a certain new and useful Improvement in the Manufacture of Quilted Linings, of which the following is a specification.

It is very desirable to economically produce linings for garments quilted, so that rows of stitching will extend obliquely from edge to edge of the linings or sections of the linings. A common form of such quilting is designated "diagonal quilting."

Quilting of the kind referred to, as ordinarily produced, is quite expensive because of the difficulty of making it.

The object of my invention is to provide for producing such quilting economically.

My improvement consists of a process for making quilted linings with rows of stitching extending obliquely between the edges, consisting in cutting out pieces of face fabric, securing the same to a strip of wadding in positions oblique with respect to the side edges of said strip of wadding, and quilting the wadding and the pieces attached thereto with lines of quilting extending in the same general direction as the edges of the wadding.

The accompanying drawings represent the principal features of a machine which may be used in practicing my improvement.

Figure 1 is a plan or top view of such machine. Fig. 2 is a central vertical longitudinal section of the same.

Similar letters of reference designate corresponding parts in both figures.

A designates a strip of wadding or like material.

B designates pieces of a face fabric—such, for instance, as silk or satin. These pieces are cut into shape suitable for forming sections of ladies' cloak-linings. The pieces or sections of lining B are secured in oblique positions to the strip of wadding. They may be thus secured by tacking them with mucilage or other adhesive substance at a suitable number of points to the strip of wadding or like material. Straight lines of stitching extending parallel with the edges of the strip

50 A will, owing to the oblique position of the

pieces or sections of lining B upon said strip, extend diagonally of said pieces or sections.

The machine which I have illustrated consists, essentially, of a needle-bar C, having a single row of needles c, which will operate 55 with any of the ordinary adjuncts, and which have merely an up-and-down motion.

The strip of wadding or like material having the pieces or sections of lining B secured to it will have a straightforward feed. In 60 other words, it will move at right angles to the row of needles. Feed-rollers D and tension-rollers E serve to present and feed the strip, with the pieces or sections B upon it, properly beneath the needles. Obviously the 65 needle-bar or the feed and tension rollers may have a lateral movement, if desirable, so as to impart more or less sinuosity to the lines of stitching with which the goods will be quilted.

After the quilting has been done the strip 70 of wadding or like material may be cut around the edges of the pieces or sections B as may be requisite. I do not wish to be understood that the face fabric must be cut into the exact form of sections of lining before being 75 treated according to my improvement. Obviously it may be cut into any styles of pieces, which may be arranged obliquely, and subsequently cut to form sections of linings.

By my invention diagonal quilting, which 80 has heretofore been a difficult and expensive style of quilting to produce, may be performed in a very simple and economical manner for linings of garments.

What I claim as my invention, and desire 85 to secure by Letters Patent, is—

The process of making quilted linings with rows of stitching extending obliquely between the edges, consisting in cutting out pieces of face fabric, securing the same to a strip of 90 wadding in positions oblique with respect to the side edges of said strip of wadding, and quilting the wadding and the pieces attached thereto with lines of quilting extending in the same general direction as the edges of 95 the wadding, substantially as specified.

CHAS. T. WAGNER.
